UNITED STATES PATENT OFFICE.

JOHANN G. WALLMANN, OF OAKLAND, CALIFORNIA.

THERMOSTAT.

1,112,743.

Specification of Letters Patent.

Patented Oct. 6, 1914

Application filed March 18, 1913. Serial No. 755,223

To all whom it may concern:

Be it known that I, JOHANN G. WALLMANN, a citizen of the United States, residing at the city of Oakland, in the county of Alameda and State of California, have invented certain new and useful Improvements in Thermostats, of which the following is a specification.

My invention relates to improvements in
thermostats.

10 The object of my invention is to provide a thermostat or thermo switch which can be so adjusted that a radiator, for example, in connection with which it may be used, 15 having reached the desired temperature, the circuit will be opened, and the same not closed again until the radiator has cooled to the amount of several degrees of heat.

Other advantages of my invention will
20 hereinafter appear.

My invention consists in the combination and arrangement of parts shown in the accompanying drawing, described in the following specification and claimed in the appended claims.

Referring to the accompanying drawing, the same is an elevation of said thermostat.

In the drawing, a bar 39 is composed of a strip of steel as its upper layer and a strip of copper as its lower layer, the said strips being brazed together and are held in place by screws 43 as shown. A bar 40 is composed of a strip of copper as its upper layer and a strip of steel as its lower layer, the same being also held in place by said screws 43 as shown. A link 45 is brazed on the free end of said bar 40 and the upper dog 47 is fitted into said link. The upper end of said link is provided with a roller 46. A spring bar 48 has its inner side of copper and its outer side of steel, the same being brazed together, said spring bar is united to the lower dog 54 at its upper end and at its bottom to post 49, preferably of brass.

45 The part 50 constitutes a coil and 87 is a square laminated core which is slideable upwardly and downwardly in said coil, the said core being fitted at its upper end to post or rod 49.

50 51 represents a bracket connected to rod 49.

Fiber insulation 52 is held in place by screw 72.

56 designates a contact holder and arm
55 for contact carbon 57.

53. represents fiber insulation held in

bracket 55, and said bracket engages arm 56 when laminated core 87 falls in the operation with bracket 51.

Contact carbon 58 is held by spring contact arm 59. The said contact arm 59 is held by binding screw 60 to insulated base 61, said base 61 being held by screws to bracket 62.

63 is a carbon contact. Insulated frame 65
40 by its screw 70 being tapped into contact
63, holds it firmly in place; and said screw
also acts as a binding post for wire 82. Con-
tact carbon 64 is screwed into insulating
fiber 65, which in turn is screwed into base
66 said base being mounted on said fiber. 70

67 is an adjusting screw tapped through bar 39.

68 represents a lock nut. A wire 81 is soldered into carbon 64 and fixed under binding post 71. A wire 80 connected as shown completes the circuit to the coil 50.

41 and 42 represent adjusting screws.

141 is an adjustable stop screw for laminated core 87. 80

142 shows an adjusting screw turnable in a fixed support as shown; and 143 is a tension spring connected to link 45.

38 shows an iron base plate. 85
A safety valve 73 is controlled by handle 74, and the circuit may be broken by hot steam, escaping from said safety valve, contacting with thermo bars 39 and 40.

As soon as the steam pressure reaches the blowing-off point as set by the suitable safety-valve 73, the steam generated escapes and is blown against and around the thermo-bars 39 and 40. The said bars as well as bar 48 are constructed of dissimilar metals so as to expand unequally on the application of heat, resulting in bending the strips. Thereupon the downward movement or bending of the bar 40 carries the bracket holding the dog 47 downwardly and bar 39 bending upwardly under the influence of the heat 100

wardly under the influence of the heat allows the arm 45 of the dog 47 to be drawn outwardly, causing dog 47 to unlatch from dog 54, the tension spring 143 aiding in drawing arm 45 outwardly. The operation of the steam heat on the spring and thermobar 48 causes the said bar to bend slightly which aids in dog 54 releasing itself from dog 47. The unlocking of dogs 54 and 47 causes the laminated core 87, which is connected as shown, to drop by gravity. As core 87 falls, bracket arm 51 which holds

carbon contacts 57 and 58 together drops with the core, and said parts 57 and 58 break the circuit. The break being connected with the heating unit in series, the 5 unit ceases to generate steam and the radiator with which the device may be connected, for example, gradually cools off. Bars 39, 40 and 48 thereupon return to their normal 10 positions. As bars 39 and 40 approach each other more closely they cause carbon contacts 63 and 64 to come together, closing the circuit through the magnet coil 50, which is now in series with the electric heating unit. Tracing the circuit as it now stands we have 15 electric connection by wire 77 to binding post 76, by wire 79 through coil 50, by wire 80 to binding post 71, by wire 81 to carbon 64, through carbons 64 and 63 to connection 70, by wire 82 to connection 60, by wire 78 20 to the electric heating unit. This closed circuit as it now stands causes coil 50 to raise the laminated core 87, causing dog 54 to catch on dog 47. Arm 51 which is fastened to the core simultaneously raises arm 56, 25 bringing carbons 57 and 58 together. The device is now on the running circuit, the switching circuit being in shunt, causes the magnet coil to weaken on account of receiving little or no current, and relaxing its upward pull on the laminated core 87—this allows the full weight of the core and its parts to hang on dog 47, which causes part 40 to bend downwardly slightly, breaking the two carbons 64 and 63 apart, whereby the switching 30 circuit is opened, allowing the full load now to be carried over the wire 77 to connection 76, by arm 56 through carbons 57 and 58, by spring arm 59, by connection 60, by wire 78 to and in series with the electric 35 heating unit. A current conducting-wire leads to terminal post 76, and 78 is such wire leading to contact arm 59 beneath screw 60.

The device does away with the necessity of turning on or off the current by hand 40 when in the case of a steam radiator, wherein the steam is generated by an electric current consuming element or unit, the said radiator reaches the desired temperature. The device may also be used as a safety device 45 and automatic shut-off for steam boilers that are used for steam cooking, providing that said boilers are heated by an electric current, and may also be so used for electric-heated hot water boilers.

50 55 I claim:—

1. In a thermostat, an electric coil, a slide- 50 able core extending through said coil and having a post leading upwardly therefrom; a resilient thermo-bar secured to the upper end of said post; an upper horizontal thermo-bar secured at one end; a lower horizontal thermo-bar secured at one end; a resilient link connected to the free end of said lower horizontal thermo-bar and mov- 65 ably engaging the underside of said upper

horizontal thermo-bar in proximity to its free end; separable locking-mechanism connecting and between said link and said resilient thermo-bar; an upper contact-carbon in connection with said upper horizontal thermo-bar, and a lower contact-carbon opposed to said contact-carbon and supported by said lower thermo-bar; a contact carbon below said lower horizontal thermo-bar and resiliently supported by an arm 70 fixed at one end and extending from said contact-carbon; a contact-carbon opposed to the contact-carbon last mentioned and supported by said post and having a pivoted arm in connection therewith; current-conducting means connected to said pivoted arm and running from said pivoted arm to and in connection with said upper contact-carbon, current-conducting means 75 running to said pivoted arm and in connection with said arm, and current-conducting means in connection with said fixed arm and extending to and in connection with said lower contact-carbon.

2. In a thermostat, the combination of an electric coil, a slideable core extending through said coil and having a post leading upwardly therefrom; a resilient thermo-bar secured to the upper end of said post; an upper horizontal thermo-bar secured at 80 one end; a lower horizontal thermo-bar secured at one end; a resilient link connected to the free end of said lower horizontal thermo-bar and movably engaging the underside of said upper horizontal thermo-bar in proximity to its free end; separable locking-mechanism connecting and between said link and said resilient thermo-bar; an upper contact carbon in connection with said upper horizontal thermo-bar, and a lower 85 contact-carbon opposed to said contact-carbon and supported by said lower thermo-bar; a contact-carbon below said lower horizontal thermo-bar and supported by a fixed support in connection therewith; a contact-carbon opposed to the contact-carbon last mentioned and connected to and supported by said post; current-conducting means in 90 connection with the contact-carbon last mentioned and extending to and in connection with said upper contact-carbon; and current-conducting means extending to and in connection with said contact-carbon below said lower horizontal thermo-bar and extending to and in connection with said lower 95 contact-carbon.

3. In a thermostat, the combination with a safety valve of an electric coil, a slideable core extending centrally through said coil and having a post leading upwardly therefrom, a resilient thermo-bar secured to the upper end of said post; an upper horizontal thermo-bar secured at one end; a lower horizontal thermo-bar secured at one end; a resilient link connected to the free end of 100 said lower horizontal thermo-bar and movably engaging the underside of said upper

said lower horizontal thermo-bar and movably engaging the lower side of said upper horizontal thermo-bar in proximity to its free end; separable locking mechanism connecting and between said link and said resilient thermo bar; an upper contact-carbon in connection with said upper horizontal thermo-bar, and a lower contact-carbon opposed to said contact-carbon and connected to said lower thermo-bar; a contact carbon below said lower horizontal thermo-bar and supported by a fixed support in connection therewith, a contact-carbon opposed to the contact carbon last mentioned and connected to and supported by said post; current-conducting means in connection with the contact-carbon last-mentioned and extending to and in connection with said upper contact-carbon; and current conducting means extending to and in connection with said contact-carbon below said lower horizontal thermo-bar and extending to and in connection with said lower contact-carbon.

4. In combination with a safety valve: an electric coil; an adjustable and slidable laminated core in said coil and having a post leading upwardly therefrom; a resilient thermo-bar secured to the upper end of said post; a resiliently connected link above said resilient thermo-bar; separable locking mechanism consisting of a pair of engageable dogs between and connecting said link and said resilient thermo-bar secured at one

end; an upper thermo-bar engaging said link; a lower thermo-bar fixed at one end and at the other end connected to said link; a binding post above said upper thermo-bar; an upper-contact carbon and a lower contact-carbon between and in connection with said upper thermo-bar and said lower thermo-bar, said contact carbons being separably opposed and said upper contact carbon being in electrical connection with said binding post and said lower contact carbon having current-conducting means in connection therewith; a contact carbon below said lower thermo-bar resiliently supported from an insulated base, said base having electrical connection with said lower contact-carbon; a contact carbon opposed to said resiliently supported contact carbon and supported on one side by said post and on the other side supported by a pivoted arm in connection therewith; electrical connection between said pivot and said coil; a current-conducting wire leading from said binding post to said coil, and current-conducting wires for electrically feeding said device and leading to said pivoted arm and said insulated base.

In testimony whereof, I affix my signature in presence of two witnesses.
